[57] CLAIM

The ornamental design for a course plotter, as shown and described.

DESCRIPTION

FIG. 1 is a top plan view of a course plotter showing my new design, with the bottom plan view being a mirror image;

FIG. 2 is a front elevational view, with the rear elevational view being a mirror image; and

FIG. 3 is another top plan view thereof, shown in an alternate position.

FIG. I

FIG. 2

FIG. 3
